UNITED STATES PATENT OFFICE.

NORBERT PERRAULT, OF OTTAWA, CANADA.

RAILWAY-CROSSING SIGNAL.

SPECIFICATION forming part of Letters Patent No. 724,395, dated March 31, 1903.

Application filed December 15, 1902. Serial No. 135,202. (No model.)

To all whom it may concern:

Be it known that I, NORBERT PERRAULT, a subject of the King of England, residing at Ottawa, county of Carleton, Province of Ontario, Canada, have invented certain new and useful Improvements in Railway-Crossing Signals; and I do hereby declare that the following is a full, clear, and exact description of the invention, such as will enable others skilled in the art to which it appertains to make and use the same.

My invention relates to railway-signals, and is especially adapted for use at railway-crossings for the purpose of giving warning of an approaching train. In its general construction it comprises a signal or sign, which is displayed to passers-by at the proper times as a warning, but which is normally in a less conspicuous position or condition, this signal being automatically operated by the approach or departure of a train.

The invention consists in the construction and combination of parts to be more fully described hereinafter and definitely set forth in the claims.

In the drawings, Figure 1 represents a portion of a railway-track supposed to be at or near a crossing, showing the application of my invention, the parts being shown, however, largely diagrammatical, as will appear. Fig. 2 is a substantially vertical section, upon an enlarged scale, showing the arrangement of a portion of the signal-operating mechanism. Fig. 3 is a substantially vertical section, also upon an enlarged scale, representing one of the automatic devices for controlling the aforesaid signal. Fig. 4 is a vertical section taken substantially on the line 4-4 of Fig. 3. Fig. 5 is a detail front elevation of the signal and the upper portion of the signal-shaft.

Throughout the specification and drawings the same numerals of reference denote like parts.

Referring more particularly to the parts, 1 represents a railway-track, supposedly at or near a grade-crossing. At a convenient point I provide a substantially vertical shaft 2, provided at its upper extremity with a signal, such as that shown at 3. It should be understood that this shaft is rotatable and carries rigidly a bevel-gear 4, which bevel-gear meshes with a bevel-gear 5, carried upon a

horizontal shaft 6. The shaft 6 is preferably disposed substantially at right angles to the direction of the track and extends to a point 55 substantially under the adjacent rail 7, at which point it is provided with a pair of rigidly-mounted ratchet-wheels 8 9, the teeth of which incline in opposite directions, as will be readily understood, and pawl-plates 10 and 60 11 are loosely mounted upon the aforesaid shaft 6, which carry pawls 12, which may engage with the teeth of their corresponding ratchet-wheels, as will be readily understood, being constrained for this purpose by the 65 leaf-springs 13. As shown in Fig. 2, this mechanism just described and other parts connected therewith are inclosed in a suitably-formed box 14.

The pawl-plates 10 and 11 are preferably 70 formed, as indicated, with upward extensions or wings 15, to which are attached clevises 16 17, and to these clevises are respectively attached the pull-wires 18 19, which extend in opposite directions, as indicated, to remote 75 points upon the track. Springs 20 press against the side walls of the box 14 and normally maintain the pawl-plates 10 and 11 in the position in which they are shown in Fig. 2. When in this position, it should be observed that the pawls 12 are held disengaged from their ratchet-wheels by means of the upwardly-curved fingers 21, which are attached to the side walls of the box and project into the path of the pawls, as will 85 be readily understood. It should appear further that if a pull were given upon either of the pull-wires 18 19 in the direction of the arrows shown in Fig. 2 the corresponding pawl-plates would be rotated upon the 90 shaft 6, the commencement of such a rotation being accompanied by the release of its corresponding pawl, so that it could then engage with its corresponding ratchet-wheel, whereupon the continued movement of the 95 pull-wire would then effect a rotation of the shaft 6, so that it could move the signal.

The devices for actuating the pull-wires are two in number, substantially similar in construction and located at more or less remote points along the track. They are indicated by the numerals 22, and it should appear that they constitute a portion of the rail 7. The construction of one of these devices

is most clearly shown in Figs. 3 and 4. It should appear that it comprises an elongated bar or member 23, adapted to be secured in the same manner as a rail, being provided 5 with a central longitudinal recess or chamber 24, opening upon its upper face. It should further appear from an inspection of Fig. 3 that this recess is formed at one extremity with a shelf or ledge 25, for a purpose which 10 will appear hereinafter, and adjacent to this shelf there is provided an inclined face 26, between which there is an elevated face 27. At its opposite extremity, however, the recess extends longitudinally into the body of the 15 bar, passing beyond the edge 28, as shown, so as to form a recess 29, which is open only at the side. Within the lower portion of this recess 24 there are provided a plurality of blocks 30, preferably substantially triangular 20 in section, their horizontal faces resting upon the bottom of the recess, as indicated. Between these blocks 30 are provided a plurality of similar blocks 31, the horizontal faces 32 of which are in substantial alinement. At that 25 extremity having the recess 29 (which extremity is, by the way, the more remote from the signal) there is provided a specially-formed block 33, which is received by the recess 29 and has an inclined face 34 and an 30 elevated face 35, which is of substantially the same height as the aforesaid face 27. There is also provided a sink-bar 36, which consists, substantially, of a flat bar with 35 downwardly-turned extremities 37, which may be rounded on their upper sides, as indicated at 38, for an evident purpose, and this sink-bar lies in the upper portion of the aforesaid recess 24. By means of a suitable fastening device 39 the pull-wire 19 is attached to the 40 block 33, and it should be understood that the tension in this wire normally maintains the member 33 in the dotted position in which it is shown at 33^a, and when this condition of affairs exists the triangular blocks 30 are of 45 course held close together, wherefore they maintain the coöoperating blocks 31 in the elevated position in which they are indicated in dotted outlines. This operates to normally maintain the sink-bar 36 in an elevated 50 position, such as that in which it is indicated at 36^a in dotted outline. When, however, a train is passing, one of its wheels, as indicated in dotted lines at 40, will depress the sink-bar 36, whereupon the blocks 30 and 31 will 55 be forced into the relation in which they are shown in full lines, and this operates to advance the block 33, as will be readily understood, so that a pull is given upon the corresponding pull-wire. 60 It should be stated that the device shown in Fig. 3 is comparatively short in length; but in practice it is expected that this device will be of such length as to insure its being always in contact with a wheel of the train, 65 so that the sink-bar would be maintained continuously depressed until the train had passed, and the parts will be so proportioned

that the resultant advance of the block 33 would effect a revolution of the signal-shaft through ninety degrees, and it may be further stated that the signal is normally maintained substantially at right angles to the railway-track, as shown at 4^a in Fig. 1 in dotted lines. The parts of the mechanism in this figure are shown substantially in the relation they assume when either of the track devices 22 is being held depressed, as will be readily understood.

The mode of operation of the entire mechanism may be now briefly described. The 80 signal 4 is normally maintained in the position 4^a, in which it presents an edge toward one approaching along the roadway. When a train is approaching, however, its wheels depress one of the devices 22 and maintain 85 the same depressed until the train has completely passed. This operates to throw the signal 4 into a right-angled position, so that it is conspicuously presented to view. The train having passed, the signal is returned automatically by either of the springs 20 to its normal position. The fact that there are two devices 22 enables the signal to be operated by trains passing in either direction. In order to effect this movement of the signal, the 90 pawl-plates are actuated, their movement effecting an engagement of their corresponding pawls with the ratchet-wheels carried by the horizontal shaft 6, the rotation of this shaft being communicated to the signal-shaft 100 2 through the bevel-gears 5 4.

While I have shown in the accompanying drawings the preferred form of my invention, it will be understood that I do not limit myself to the precise form shown, for many of 105 the details may be changed in form or position without affecting the operativeness or utility of my invention, and I therefore reserve the right to make all such modifications as are included within the scope of the following claims or of mechanical equivalents to the structures set forth.

Having thus described my invention, what I claim as new, and desire to secure by Letters Patent, is—

1. In a device of the class described, in combination, a substantially vertical shaft, a sign carried thereby, a substantially horizontal shaft adapted to drive said first shaft, ratchet-wheels carried by said horizontal shaft, pawls 120 coöperating therewith, said ratchets and pawls being adapted to rotate said horizontal shaft in either direction, springs normally constraining said pawls so that they are disengaged from said ratchet-wheels, pull-wires 125 adapted to actuate said pawls, and automatic track devices adapted to actuate said pull-wires, said sign being normally maintained with its edge presented toward the roadway.

2. In a device of the class described, in combination, a substantially vertical shaft, a sign carried thereby, a second horizontal shaft adapted to rotate said first shaft, said horizontal shaft being disposed substantially at

- right angles to the direction of the rails, ratchet-wheels rigidly carried thereby, the teeth whereof are disposed in opposite directions, pawls coöperating with said ratchet-wheels, means for normally holding said pawls out of engagement with said ratchet-wheels, automatic track devices, and mechanism leading thereto and adapted to actuate said pawls.
3. In a device of the class described, in combination, a substantially vertical shaft, a sign carried thereby, a second and substantially horizontal shaft adapted to rotate said first shaft, said horizontal shaft being disposed substantially at right angles to the rails, a pair of ratchet-wheels rigidly carried by said second shaft, pawl-plates rotatably mounted upon said horizontal shaft adjacent thereto, pawls carried thereby, the teeth of said ratchet-wheels being disposed in opposite directions, means for constraining said pawl-plates so that said pawls are normally disengaged from said ratchet-wheels, and automatic track devices adapted to actuate said pawl-plates.
4. In a device of the class described, in combination, a substantially horizontal shaft, a sign adapted to be controlled thereby, said shaft being disposed substantially at right angles to the direction of the railway, ratchet-wheels rigidly carried by said shaft, the teeth whereof are disposed in opposite directions, pawl-plates rotatably mounted upon said shaft adjacent to said ratchet-wheels, pawls carried thereby, springs normally constraining said pawl-plates, members projecting into the path of said pawls, wherefore they normally maintain the same out of engagement with said ratchet-wheels, pull-wires connected with said pawl-plates, and automatic track devices adapted to actuate said pull-wires.
5. In a device of the class described, in combination, a danger-sign, a substantially horizontal shaft adapted to control the same, said shaft being disposed substantially at right angles to the direction of the railway, a pair of ratchet-wheels rigidly carried by said shaft and having oppositely-disposed teeth, pawl-plates rotatably mounted upon said shaft, pawls carried thereby, springs therebehind and constraining said pawls toward said ratchet-wheels, springs constraining said pawl-plates, and members projecting into the path of said pawls and normally adapted to maintain the same out of engagement with said ratchet-wheels, pull-wires connecting with said pawl-plates, and automatic track devices adapted to actuate said pull-wires.
6. In a device of the class described, in combination, a substantially horizontal member adapted to be depressed by the wheel of a passing train, a plurality of members therebelow having inclined faces, a signal, and mechanism connecting said signal with said members.
7. In a device of the class described, in combination, a plurality of blocks having inclined faces, a member resting thereupon and adapted to be depressed by the wheel of a passing train, a signal, mechanism connecting said blocks with said signal, and a spring normally constraining said blocks so that they are in an elevated position, said member being adapted to depress said blocks.
8. In a device of the class described, in combination, a member adapted to constitute a portion of the rail, said member having a recess, a plurality of blocks having inclined faces carried within said recess, a spring normally constraining said blocks so that they are held in an elevated position, a sink-bar carried within said recess and resting upon said blocks, said sink-bar being adapted to depress said blocks, a sign, and mechanism connecting said blocks with said sign.
9. In a device of the class described, in combination, a member adapted to substantially constitute a portion of the rail, said member having a recess, a plurality of blocks with inclined faces mounted within said recess, a spring constraining said blocks longitudinally of the rail, wherefore they are normally maintained in an elevated position, a sink-bar resting upon said blocks and projecting above the upper face of said rail, a signal, means for longitudinally guiding one of said blocks within said recess, and a pull-wire connecting the same with said signal.
10. In a device of the class described, in combination, a signal, a shaft adapted to control the same, ratchet-wheels rigidly carried by said shaft and having oppositely-disposed teeth, pawl-plates adjacent to said ratchet-wheels, pawls carried thereby and adapted to coöperate therewith, members constituting substantially portions of the rail, bars carried thereby and adapted to be depressed by the wheel of a passing train, a plurality of blocks below said bars and adapted to support the same normally in an elevated position, pull-wires connecting said blocks with said pawl-plates, and springs constraining said pawl-plates and said blocks, whereby said blocks are normally maintained in said elevated position.
11. In a device of the class described, in combination, a sign, a shaft adapted to control the same, a pair of ratchet-wheels rigidly carried thereby and having oppositely-disposed teeth, pawl-plates, pawls carried thereby, members adapted to project into the path of said pawls, a pair of bars located respectively upon the track and on opposite sides of said sign, said bars being adapted to be depressed by the wheels of a passing train, members adjacent respectively to said bars, means whereby the depression of said bars may displace said members, pull-wires respectively connecting said members with said pawl-plates, and springs constraining said pawl-plates and maintaining said bars normally in an elevated position, said members normally maintaining said pawls out of engagement with said ratchet-wheels.

12. In a device of the class described, in combination, a sign, pull-wires extending in opposite directions along the track, mechanism therebetween for actuating said sign, springs normally constraining said mechanism so that it is maintained in a disengaged relation, members adapted to be depressed by a passing train, mechanism connecting the same with said pull-wires, means whereby the depression of said members may throw said first mechanism into engagement to control said sign, said springs affording means to normally maintain said members in an elevated position.
13. An automatic railway-crossing guard comprising a vertical rotatable shaft, a sign mounted on its upper end, a bevel-gear mounted on its lower end, a horizontal shaft transverse to the track, a bevel-gear mounted thereon and intermeshing with said first gear, a lever operatively connected with said horizontal shaft, a depressible track device inserted in the track at a distance from the crossing, and a connection between said lever and track device, whereby said lever is caused to be rotated by the depression of the device.
14. An automatic railway-crossing guard comprising a vertical rotatable shaft, a sign mounted on its upper end, a bevel-gear mounted on its lower end, a horizontal shaft transverse to the track, a bevel-gear mounted thereon and intermeshing with said first gear, a pair of ratchet-wheels keyed to said horizontal shaft and having their teeth facing in opposite directions, a pair of pawl-levers loosely mounted on said shaft and carrying pawls adapted to engage with the respective gears, means for normally holding said pawls out of engagement with said gears, track devices connected with said pawl-levers to rotate the same on the passage of a train thereover, and retractile springs adapted to return the levers to their normal position after the passage of the train.
15. In an automatic railway-crossing guard, a track device comprising a depressible bar over which the wheels are adapted to roll, and a series of triangular blocks interlocking with one another beneath said bar and adapted to slide laterally, the block at one end being seated against a fixed abutment.
16. In an automatic railway-crossing guard, a track device comprising a depressible bar over which the wheels of a train are adapted to roll, a series of loose triangular blocks adapted to slide in upright position on a longitudinal base, a series of inverted triangular blocks interlocking with the blocks of the first series and on the bases of which said depressible bar rests, a fixed abutment for the block at one end of the series, and an operative connection for a cable or wire at the other end of the series, whereby a slight depression of said track device causes an increased horizontal movement of the wire or cable attached to said device.
17. In an automatic railway-crossing guard, a track device comprising a chambered casting inserted in the rail and forming a part thereof, a depressible bar closing the upper side of the chamber of said casting and normally rising a slight distance above the upper side of the casting, a series of upright triangular blocks having the ends of their bases cut away and arranged to slide loosely on the base of said casting, a series of inverted triangular blocks similar to the first series and on whose bases said bar is adapted to loosely rest, a fixed abutment against which the block at one end of the inverted series is adapted to slide, a sliding block forming an abutment for the inverted triangular block at the other end of the series, and a bolt extending sidewise through a slot in the casting and secured to said sliding block and forming means for connecting a wire or cable.
- In witness whereof I have hereunto set my hand in the presence of two witnesses.
